UNITED STATES PATENT OFFICE.

JAMES G. GRAINGER, OF CENTRALIA, WASHINGTON.

PALLET SETTER-GAGE.

1,316,299.

Specification of Letters Patent. Patented Sept. 16, 1919.

Application filed December 16, 1918. Serial No. 266,930.

To all whom it may concern:

Be it known that I, JAMES G. GRAINGER, a citizen of the United States, residing at Centralia, in the county of Lewis and State 5 of Washington, have invented a new and useful Pallet Setter-Gage, of which the following is a specification.

This invention has reference to gages for properly setting the jewels in pallets of different makes of watches, and its object is to provide a gage whereby the jewels, whether already present in the pallets or replacing broken or lost jewels, may be accurately set whether or not the watch movement be 15 present.

In accordance with the invention, there is provided a body member, which may be in the form of a plate, with holes or receptacles therein, wherein the pallet arbors may be seated and associated with the holes is a slide whereby the pallet jewels may be accurately placed, certain lines being provided for lining up the pallets with respect to the slide so that when the jewels are inserted 25 into touching relation to the slide accurate positioning is assured.

The invention will be best understood from a consideration of the following detailed description taken in connection with 30 the accompanying drawing forming part of this specification, with the understanding, however, that the invention is not confined to any strict conformity with the showing of the drawing but may be changed and modified so long as such changes and modifications mark no material departure from the salient features of the invention as expressed in the appended claims.

In the drawing:—

40 Fig. 1 is a face view of a pallet gage with a pallet in position thereon.

Fig. 2 is a section on the line 2—2 of Fig. 1.

Fig. 3 is a face view of the opposite side 45 of the gage with the parts in somewhat different position from that shown in Fig. 1.

Fig. 4 is a view of the slide removed from the body of the gage.

Fig. 5 is a section on the line 5—5 of 50 Fig. 3.

Fig. 6 is a detail view showing the operation of the gage with respect to a different form of pallet from that shown in Fig. 1.

Referring to the drawing, there is shown 55 an elongated rectangular plate 1 constituting the body of the gage, such particular

form of body member not being obligatory but at the same time providing a convenient body member for the gage.

Mounted on the body member is a slide 2 conveniently formed of face strips 3, 4 and end strips 5. The face strips 3 and 4 extend across the respective faces of the plate 1 and have edge portions 6 at a slight angle to the width of the plate. In the strips 3 and 4 are recesses 7 to accommodate certain parts of the pallets.

The body member or plate 1 is also provided with another slide 8 designed to serve as a follower for the slide 2. The slide 8 is 70 provided in the edge toward the slide 2 with recesses 9.

The body member or plate 1 has rows of holes or perforations 10 extending lengthwise of the body member and in the particular showing of the drawing there are two of such rows of holes about equidistantly spaced from the edges of the body member 75 1 and from each other. The invention is not confined to any such particular arrangement 80 but with a gage of moderate size, say about three and one-half inches long and one inch wide, practically all makes of pallets may be accommodated.

In Figs. 1 and 2 there is shown a pallet 85 11 with jewels 12, a fork 13 at one end and an arm 14 at the other end, this being a form of pallet employed in certain watches. In Fig. 6 there is shown another form of pallet 15 having jewels 16 with a fork 17 arranged 90 at right angles to the arrangement shown in the pallet 11. Each pallet has an arbor 18 and the holes 10 in the rows of holes are so arranged as to receive the arbors or staffs 18 of different makes of pallets. 95

The holes or receptacles 10 are arranged in rows lengthwise of the plate 1 and extending crosswise of the plate so as to each intersect a hole 10 are lines 19, the longitudinal rows of holes being joined by other 100 lines 20. Moreover, the end straps or guide bars 5 which engage and move along the edges of the plate 1 and are of greater length than the width of the strips 3 and 4 have each a mark or line 21 to register with any 105 one of the lines 19.

The plate 1 is provided with symbols, words, letters or numbers related to the holes 10 to designate the holes to guide the workman with respect to the particular holes 110 to be chosen for the particular make of watch so as to place the arbor or staff of the

chosen pallet therein. Then the follower slide 8 is moved, in the case of a staff 11, so that the lever end 14 is seated in a recess 9 with the fork 13 alined with the line 20 and located in a proper recess, or the pallet 15 has its fork 17 extended along a proper line 19. Then the slide 2 is moved toward the pallet 11 until the proper line 21 on the adjacent side bar 5 alines with the same line 19 that traverses the hole 10 in which the arbor 18 is lodged.

If the jewels 12 or 16, as the case may be, are properly set, then they will both just touch of the edge 6 of the bar or strip 3 or 4. If, however, these jewels be improperly set then one or the other or neither may be touched by the edge 6 of the slide 2 when the slide is properly positioned with relation to the chosen line 19, showing the necessity of adjustment of the jewels. If one or the other or both of the jewels be too long then the cement holding the jewel or jewels in the pallet must be softened and the jewel be properly adjusted. If one or both jewels be broken and it be desired to replace them the slide 2 and, in the case of the pallet 11, the pallet and follower 8 must be properly adjusted, or in the case of the pallet 15, said pallet be properly adjusted, and then the jewels may be inserted and located and then cemented in the pallet.

These operations may be performed in a minimum time with the assurance that, having the parts properly set, the jewels are located and secured in place with absolute certainty of accuracy. It is not material that the watch movement be present since the gage contains information apprising the workman of the catalogue number and model and other information, such as the class of the pallet and watch movement, thus permitting the workman to properly set the gage and thereby be sure that the jewels will be properly set for the movement to which the pallet is to be applied, all guess-work and special fitting being eliminated.

Suppose, by way of example, that a watchmaker receives a pallet without a jewel in it and without the movement but receives a description of the watch it belongs to. The jewels are readily set and the pallet may be returned to be placed in the watch movement which it will then fit exactly.

Heretofore, the matching and setting of the jewels in pallets have given watchmakers the most trouble, the pallet being a vital part of the watch, but with the gage of the invention such operation is performed expeditiously and with the assurance that the matching and setting is correct even though the work be done in the absence of the watch movement.

What is claimed is:—

1. A pallet setter gage comprising a body portion with perforations to receive the ar-

bor or staff of the pallet, and a slide movable along the body member and provided with an indication for positioning the slide with respect to a chosen perforation, said slide having a portion constituting a shoulder for abutment by the jewels of the pallet when its arbor is in a chosen perforation. 70

2. A pallet setter gage comprising an elongated plate with a series of perforations extended lengthwise of the plate to receive the pallet arbor or staff, said plate having indicating lines each extending from a perforation toward the edge portion of the plate, and a slide mounted on the plate to move lengthwise thereof and having an indication for positioning the slide with respect to a line leading from a chosen perforation, said slide having a portion constituting a shoulder for abutment by the jewels of a pallet when its arbor is in a chosen perforation and the plate is positioned with respect to said perforation. 80

3. A pallet setter gage comprising a plate with a series of perforations therein for receiving the arbors or staffs of pallets, and a slide movable along the plate into definite relation to chosen ones of the perforations with a portion of the slide constituting a shoulder to be abutted by the jewels when the latter are properly set in the pallet. 90

4. A pallet setter gage comprising an elongated plate with longitudinally extended rows of perforations therein, a slide mounted on the plate to move lengthwise thereof and having shoulders extending crosswise of the plate in slanting relation to the line of travel of the slide, and means for positioning the slide with relation to any chosen perforations, said perforations constituting receptacles for the arbors or staffs of the pallets and the slanting shoulders constituting abutments for the pallet jewels whereby to position the jewels in the pallets. 100

5. A pallet setter gage comprising an elongated plate with longitudinally extended rows of perforations therein, a slide mounted on the plate to move lengthwise thereof and having shoulders extending crosswise of the plate in slanting relation to the line of travel of the slide, and means for positioning the slide with relation to any chosen perforations, said perforations constituting receptacles for the arbors or staffs of the pallets and the slanting shoulders constituting abutments for the pallet jewels whereby to position the jewels in the pallets, and the means for positioning the slide with relation to chosen perforations comprising markings on the slide and plate with the markings on the plate intersecting the respective perforations. 110

6. A pallet setter gage comprising an elongated plate with serially arranged perforations therethrough for receiving the arbors or staffs of pallets, a slide on the plate mov- 120

130

able lengthwise of the series of perforations into determined relation to said perforations, and a follower on and movable along the plate and provided with receptacles for parts of the pallets whereby the pallets may be alined with the line of movement of the slide along the plate.

In testimony that I claim the foregoing as my own, I have hereto affixed my signature.

JAMES G. GRAINGER.
